UNITED STATES PATENT OFFICE.

ISAAC A. SOWDER, OF CHATTANOOGA, TENNESSEE, ASSIGNOR TO D. M. STEWARD MANUFACTURING COMPANY, INC., OF CHATTANOOGA, TENNESSEE, A CORPORATION OF TENNESSEE.

RADIOSTABILIZER.

Application filed June 24, 1925. Serial No. 39,321.

This invention relates to improvements in radio apparatus, and more particularly to means of stabilizing tuned circuits for the amplification of radiofrequency oscillations. It has heretofore been proposed to employ electron discharge tubes connected in cascade for the amplification of radiofrequency oscillations, and to effect the successive connections between the respective tubes by means of transformers. The resistances of such circuits are substantially constant, but the impedances of the external circuits vary as the apparatus is tuned for the various frequencies. The tendency therefore is for the apparatus to become unstable as an amplifier at the higher frequencies corresponding to wave-lengths of about 300 meters, depending upon the losses in the particular apparatus. The apparatus at such an unstable point was critical and was easily thrown into continuous oscillation.

Various means have been suggested to prevent the occurrence of such critical points within the range of frequencies employed at the present day for broadcasting. Such means have been of the "loss stabilizer" type in which the operation depended upon the introduction of a loss by purely ohmic resistance into the grid circuit of the apparatus: or of the "balancing" or "neutralizing" types, in which the capacity of the tube itself was balanced out by a shunting condenser, and the other impedance effects were compensated by split inductances and the like.

The compensation of the set requires a continuous adjustment for each wave-length to be received. With loss stabilizers, the resistance introduced was usually of the potentiometric type, and advanced by steps, so that no regular gradation to suit the various waves was attainable. Furthermore, with many such circuits, the inclusion of a certain portion of the loss resistance was necessary for the operation of the apparatus even at higher wave-lengths. With balancing systems, it is usually necessary to balance each tube separately: and usually once for all at one of the desired wave-lengths.

According to the present invention, a stabilizer is provided for radiofrequency amplifiers, which enables the operation of the ap-

paratus at substantial resonance at any wavelength; and allows the operator to immediately and exactly eliminate any tendency toward oscillation. The successive stages are connected by air-core transformers and these transformers have their fields restricted or confined, and their effective impedances controlled, by the stabilizing system. Preferably a certain arrangement of the transformer coils is employed, and the potential of the stabilizer mechanism with respect to the coils is defined.

By way of illustration, this invention is demonstrated in connection with an apparatus employing two radiofrequency amplifying tubes and a detector, but it will be understood that such arrangement is not compulsory, and that more or less tubes may be employed, and that the currents from the amplifying apparatus may be used for any purpose desired.

In the drawings:

Fig. 1 shows a diagram of such a circuit, with a stabilizer applied to the grid transformer of the second radiofrequency amplifying tube.

Fig. 2 shows a top plan of such an apparatus.

Fig. 3 shows the corresponding rear view.

Fig. 4 shows a support in perspective.

The antenna 10 is connected through an inductance 11 to the ground at 12. This inductance 11 constitutes the primary of a transformer T_1 , having the secondary 13 which may be tuned by the variable condenser 14, and has one terminal connected to the grid of the first radiofrequency amplifying electron discharge tube A, and the other terminal connected to the filamentary cathode of this same tube.

The plate of this tube A is connected to the reversed primary 15 of a second transformer T_2 , and thence to the common plate battery conductor 16, the common plate battery 17, and by the return bus wires 18, 19, to the cathode of the tube A. This transformer T_2 has a secondary 20 which may be tuned by the variable condenser 21, and has one of its terminals connected to the grid of the second amplifying tube B, and the other terminal to the filamentary cathode of this same tube B.

The plate of the tube B is connected to the primary 22 of a further transformer T_3 , and thence to the common plate battery conductor 16, the plate battery 17, with a return 5 as before to the filament of the tube B. The transformer T_3 has a secondary 23 which may be tuned by a variable condenser 24, and which has one of its terminals connected through the customary grid leak and condenser 25 to the grid of the detector tube D, and the other terminal connected to the filamentary cathode of this tube D.

The plate of the tube D is connected through the indicating instrument 26 and 15 wire 27 to an appropriate portion of the plate battery 17, and with a return by wire 18 to the cathode of the tube D.

The filaments are heated by the single battery 28. The amplifier tube filaments are 20 grouped and controlled by the rheostat 29, and the detector filament is connected through a separate rheostat 30. The common conductor 31 serves to connect the negative terminals of the amplifier filaments and 25 the grid returns of these tubes to the ground. The grid return of the detector tube D is connected to the positive side of the filament.

The stabilizer shown consists of a thin 30 disk 35 of magnetic conductive material such as soft iron, held at the end of a lever 36 which may be pivoted at 37 to any appropriate part of the apparatus. A coil spring 38 tends to retract the disk into one 35 end position; and a rotatable cam 39 may be utilized to move the lever against the action of the spring into regulated intermediate positions. As shown in Fig. 3, the disk 35 in its inmost position is in close 40 parallelism to and concentric with the transformer T_2 , which is illustrated as being of the air-core, flat pancake type with zigzag windings to reduce the capacity effects. In order to closely define the potential of this 45 disk, it is preferably connected by the conductor 40 to the common positive bus wire 19 of the amplifier tubes.

In operation, as the apparatus is tuned by the variable condensers 14, 21, 24, it is 50 found that as the wave-length adjustment becomes lower and lower, the circuits tend more and more to set up continuous self-oscillations. The operator can meet this condition by rotating the cam 29 to bring the 55 disk 35 more and more into the field of the transformer inductances 15 and 20. The effect is to change the effective impedance of these elements, to produce an eddy current loss by the disk of the current circulating in the inductances, to limit or confine the external magnetic fields of these coils, and to produce a capacity effect across the tube B from grid to filament in shunt of the input tuning condenser. As a total 60 results, the tendency towards oscillation is

checked: it may be remarked that this checking point is very exact and may be located and controlled easily by the operator.

A further and additional advantage of the particular arrangement shown, is that 70 after the set has been stabilized; which as indicated above occurs at a very definite and certain position for a given wave-length, a further inward movement of the disk will give a very successful regulation of the 75 volume of the output.

In Figs. 2 and 3 is shown the employment of such a circuit and arrangement of apparatus. The transformers T_1 , T_2 , T_3 are shown as mounted on supports 50, 51, 52 80 which are bolted to the rear plates 53 of the condensers 14, 21, 24. These supports are shown in detail in Fig. 4, as having the stem 54 to support the coils at a sufficient distance away from the condensers and 85 other metallic parts of the apparatus, so that their fields are substantially free from metal; and the feet 55 bent at right angles to the stem and provided with the apertures 56 to receive clamping bolts; they permit the 90 adjustment of the transformer coils to various mutual positions of distance and angle. In assembling the apparatus, it is found by trial that at certain relative angles and 95 positions of the two outer transformers, a 100 minimum reactive relation exists: the central transformer is then located so as to have a minimum reactive relation with the other two coils and especially with regard to the last transformer coil, and so that it is substantially horizontal. The disk 35 is then 105 adjusted in position so that absolute stability is attained at the lowest wave-length for which the apparatus is designed, at its inmost position.

To complete this description, it has been found upon test that very satisfactory results may be obtained if the transformer coils are of the pancake, diamond-weave, type with ten turns in the primaries and 110 about fifty-five turns in the secondaries, of one and three-quarters inches inside and three and three-quarters inches outside diameter; with a disk one and one-half inches in diameter, held parallel to and about one-half inch from the central plane of the transformer coils at the inmost and one and one-half inches from said position at the outmost position. The thickness of the disk appears to be relatively unimportant. The apparatus constructed with these elements received excellently from 175 to 600 meters.

It will be understood that these quantities are merely by way of instruction and that the invention is not limited either thereto 115 nor to the specific arrangement shown, but may be modified therefrom within the scope of the appended claims.

I claim:—

1. In a system for amplifying high fre- 130

quency electrical oscillations occurring in an input circuit, a plurality of electron discharge tubes including a first and a second amplifying tube and a detector tube, means to excite the cathodes of said tubes, means to produce a space current through each tube responsive to the input potential upon the tube, a first transformer between the said input and said first amplifying tube, a second transformer between said amplifying tubes, and a third transformer between said second amplifying tube and said detector tube, circuits to connect said input, said transformers and said tubes in cascade, a variable condenser to tune the input circuit of each tube, said transformers being of the flat wound disk type, the secondaries of all of said transformers being wound in the same direction and the primary of the second transformer being wound in opposition to those of the first and the third transformers, supports for said transformers to hold them in spaced relation and substantially free from metal in their respective fields, means to adjust the mutual distance and angle of said transformers, a disk of conductive magnetic material in the field of said second transformer coil, a lever to support said disk, and means to rock said lever to determine the position of said disk with regard to said

transformer, and a conductor from said disk to the positive terminal of said exciting means.

2. In a transformer for radiofrequency electrical oscillations, a flat primary winding, a flat secondary winding, a disk of conductive magnetic material, a lever to support said disk in parallelism with said windings, a spring to bias said lever toward one end position and move said disk away from said windings, and a rotatable cam to rock said lever against the action of said spring to move said disk toward said windings, said disk adapted to limit the external field of said windings, and to have a capacitative relation therewith.

3. In a system for amplifying high frequency electrical oscillations, a plurality of electron discharge tubes, interstage coupling transformers and associated circuits to connect said tubes in cascade relation, the primary of one of said transformers being reversed with respect to its neighbors, a disk of magnetic conductive material in the field of said reversed primary, and means to move said disk toward and away from said primary.

In testimony whereof, I affix my signature.

ISAAC A. SOWDER.
